UNITED STATES PATENT OFFICE.

PETER PEZUTO, OF CURWENSVILLE, PENNSYLVANIA.

EXERCISING APPARATUS.

Application filed January 18, 1927. Serial No. 161,886.

This invention relates to exercising devices of that character wherein an elastic element is used either connected at one end to a wall or like support and provided at its 5 opposite end with a handle or handles, or used as a chest expander, as it is called, where the elastic element is provided with handles at both ends.

The general object of the invention is to 10 provide a device of this character which may be readily changed so that it may be used either as a chest expander or as a wall supported exerciser.

A further object is to provide a device 15 which is compact, simply made, which may be economically produced, and in which the elastic element may be changed from time to time if it be desired to increase or decrease the strength of the elastic element or 20 if the elastic element loses its elasticity.

Other objects have to do with the details of construction and arrangement of parts to appear more fully hereinafter.

My invention is illustrated in the accompanying drawings wherein:—

Figure 1 is a front elevation of an exercising device constructed in accordance with my invention;

Fig. 2 is a vertical sectional view thereof; 30 Fig. 3 is a fragmentary section on the line 3—3 of Figure 1;

Fig. 4 is a section on the line 4—4 of Figure 1;

Fig. 5 is an end elevation of a handle 35 member with its jaws open;

Fig. 6 is a section on the line 6—6 of Figure 1;

Fig. 7 is a section on the line 7—7 of Figure 1;

Fig. 8 is a plan view showing the exercising 40 device as arranged for a chest expander;

Fig. 9 is an elevation showing the exercising device arranged for other exercises.

My improved exercising device consists of 45 an elastic element 10 which is formed preferably of a strip of highly elastic rubber or like material, such as a strip formed by or cut from an inner tube. This strip, in case the device is to be used as a chest expander, 50 is to be engaged at both ends with handles designated A, but in case the device is to be used as a wall supported exerciser, then one end of the strip 10 has engaged therewith the handle A and the other end of the strip 55 has engaged therewith the detachable yoke B, in place of the handle A, this yoke B be-

ing so formed that it may be engaged with a hook on a wall or other support.

Each handle A is formed as illustrated in Figure 1 of two parallel, relatively stiff and stout wires 11 bent to define a rectangular figure, the wires being engaged at their ends by the sleeves 12 or other suitable means and the conjoined ends of the wires being inserted within the tubular handle proper 13. It 60 will be seen that the strips 12 which constitute sleeves for the ends of the wires 11 support each yoke formed by the wire 11 in a pivotal manner so that the free ends of the yoke may be separated or may be brought 65 together for clamping engagement with the rubber strip 10. When brought together, as shown in Figure 1, the jaws thus formed are held in clamping engagement with the rubber 70 10 by means of the rings 14. These rings 75 may be slipped up on the shanks of the yoke as shown in dotted lines in Figure 1, so as to permit the opening of the jaws or may be slipped down, as shown in full lines, so as to cause the jaws to clamp the rubber strip. It 80 will be understood that there are two of the yokes A with their handles 13 and that these handle yokes may be engaged with opposite ends of the strip 10 or only one of the handles 85 yokes need be engaged with one end of the strip 10 provided the other end of the strip is engaged with some fixed support.

For the purpose of engaging one end of the strip 10 with a fixed support I provide a yoke B which is also preferably formed 90 of two wires 15 disposed side by side with the ends of the wires disposed within the hollow sleeves 16. Each sleeve 16 is preferably trifoliate in cross section so as to provide three partially circular recesses within 95 two of which the wires 15 are disposed side by side.

Disposed within the other recess are the shanks 17 of a ring 18. Thus it will be seen that both members or jaws of the yoke B are 100 capable of swinging movement within the sleeves 16 as is the hook 18. These jaws formed by the wires 15 may, however, be brought into clamping engagement with the strip 10 by the rings 19 which are capable 105 of being shifted upon the yoke to either hold the jaws in clamping position or release the jaws. I do not wish to be limited to the provision of a ring in connection with the yoke B as a hook might be provided instead 110 of the ring and I regard one as the equivalent of the other. Neither do I wish to be

limited to the exact construction of the yokes A and B as obviously details of these yokes might be varied without departing from the spirit of the invention.

5 In the use of this device, if a general exerciser is desired, two strips 10 are used, as illustrated in Figure 9, upon each one of which there is clamped a handle yoke A. The two strips are clamped between a single yoke B and this yoke is engaged with a wall or other support by means of the hook 20 which engages the ring 18. Under these circumstances, the exerciser may be used in the ordinary manner of this type of exerciser. Where it is desired to convert the device into an exerciser of the chest expander type, then the yoke B is disconnected from the strip 10, the other handle yoke A is substituted in place thereof, and the exerciser 10 can then be used in the manner indicated. It will be seen that my construction permits the substitution of a stronger or weaker strip 10 for one in use or will permit the use of two or more strips 10 between the 15 yokes A or the yokes A and B. This strip 10 may be cut wider or narrower or thicker or thinner and, as before remarked, may be made from an old inner tube. Thus the exerciser may be readily adjusted to suit the 20 amount of exercise desired.

While I have heretofore referred to the use of this exercising apparatus by grasping

the handles B and thereby expanding the elastic strips or bands 10, the apparatus may also be used by inserting the foot in one of the yokes A and raising or lowering the other yoke A by hand or the foot may be inserted in the yoke B and the handle A be raised or lowered or the yoke B may be grasped by the hand and the foot inserted in the yoke A or the construction shown in Figure 9 may be used by the exerciser lying on the floor, grasping the yoke B by his hands, and inserting his foot in the yokes A. Thus, it will be seen that a large number of different exercises may be secured by the use of this device.

I claim:

An exercising apparatus including an elastic strip and a yoke detachably engaging the end of the strip, said yoke comprising two many-sided clamping jaws open on one side, a tubular handle into which the ends of the clamping jaws are inserted, the clamping jaws being disposed in approximate contact with each other, sleeves embracing the inserted ends of the clamping jaws and permitting the clamping jaws to have swinging movement with relation to each other, and rings slidable along said jaws to or from a clamping position.

In testimony whereof I hereunto affix my signature.

PETER PEZUTO.
